(57) **CLAIM**

The ornamental design for a gate opener stand, as shown and described.

DESCRIPTION

FIG. 1 is a front view of a gate opener stand showing my new design.

FIG. 2 is a back view of FIG. 1.

FIG. 3 is a right side elevation view of FIG. 1.

FIG. 4 is a left side elevation view of FIG. 1.

FIG. 5 is a top view of FIG. 1.

FIG. 6 is a bottom view of FIG. 1.

FIG. 7 is a front perspective view of FIG. 1; and,

FIG. 8 is an environmental perspective view of the gate opener stand.

The broken lines in FIG. 8 represent environment and form no part of the claim.

1 Claim, 6 Drawing Sheets(56)
